(57) **CLAIM**

The ornamental design for a soccer rebounder, as shown and described.

DESCRIPTION

FIG. 1 is a top, front, right side perspective view of the soccer rebounder, showing my new design.

FIG. 2 is a bottom, rear, and right side perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is an enlarged view of the area labeled 9 in FIG. 1. The dot-dash broken lines encircling portions of the soccer rebounder in FIG. 1 and illustrated in enlarged views in FIG. 9 form no part of the claimed design. The broken lines in the drawings show portions of the soccer rebounder that form no part of the claimed design.
